UNITED STATES PATENT OFFICE

FREDERICK T. RUSSELL, OF UTICA, NEW YORK, ASSIGNOR TO SAVAGE ARMS CORPORATION, OF UTICA, NEW YORK, A CORPORATION OF DELAWARE

IRONING MACHINE

Application filed December 28, 1926. Serial No. 157,438.

The object of the invention is the provision of a power driven, domestic type, ironer of simplified and improved construction, capable of operation with a minimum of manual effort and constructed to permit of the assembly of the various parts in a compact and attractive form as below pointed out.

In the accompanying drawings, Fig. 1 is a perspective view of the preferred form of the complete ironing machine unit,

Fig. 2 is a larger scale view of the right-hand end of the machine,

Fig. 3 a section on the line III—III of Fig. 4,

Fig. 4 a front elevation of the machine, the right-hand end being a section on the line IV—IV of Fig. 3,

Fig. 5 is a section on the line V—V of Fig. 4, certain parts being omitted for clearness of illustration, and

Fig. 6 a view of the left-hand end of the machine.

Referring to Fig. 1, it will be seen that the machine includes a padded ironing roll 1 journaled at one end in the arm 2 of a goose-neck support 3 and supported at its other end by its shaft 4 (Fig. 4) in suitable bearings in the wall of a transmission housing or gear case generally designated 5. The goose-neck arm 2 also supports one end of a combined feed table and control board 6 pivoted thereto at 7. The other end of this pivoted table is supported on the housing 5.

Mounted in back of the roll for movement toward and from the same is an ironing shoe 8, heated electrically, although other heating means might be used. The shoe is carried by trunnions 9 in the arms 10 secured to the rock shaft 11. When the shoe is properly set with respect to the roll, rocking movement thereof on the arms 10 may be limited or prevented by any suitable means as for example by a screw, or any equivalent device, represented by 12 in Fig. 6.

The rotation of the roll and the movement of the shoe are both produced by an electric motor 13 mounted at the rear of the transmission housing (Figs. 2 and 3) and the whole machine is preferably mounted on a table 14, which although shown as provided

with its own legs, may when the legs are removed, be placed upon any other table or wherever is most convenient. The motor armature shaft is directly coupled to the main drive shaft 15 which carries a worm 16. Referring first to the drive connections of the ironing roll, it will be seen that the worm 16 drives worm-gear 17, secured to a shaft 18, which shaft carries free thereon a pinion 19 adapted to be clutched to or released from the shaft by means of the splined clutch collar 20 and clutch pins 21. The pinion 19 drives the large spur gear 22 fast on the end of the roll shaft 4, above mentioned, and thus drives the ironing roll whenever the motor is in operation and the pinion 19 clutched to the shaft 18. The clutch 20—21 is conveniently operated by means of any suitable clutch operating member such as the lever 23 (Figs. 1 and 5) pivotally mounted on the housing 5 and connected with the collar 20 by a fork or any other suitable means as will be understood. When the lever is moved to the right the clutch is opened and it is closed by the opposite movement.

Referring now to the shoe drive—the worm 16 also drives a worm gear 24 which is loosely mounted on a shaft 25 journaled in the walls of the transmission housing. By means of the clutch pins 26 and a clutch collar 27 splined to the shaft 25 the latter may be clutched to or released from the gear 24. This clutch is of the automatic throw-out type and is so organized that when allowed to be driven by the gear 24 it will rotate the shaft through one hundred and eighty degrees only and will then of its own accord come to rest. This operation is conveniently effected by means of the face cam 28 formed on the flanged part of the clutch collar 27 and adapted to engage a control pin 29 which is formed on or by the lower end of a plunger rod 30 mounted for vertical endwise movement in the outer wall of the transmission housing and normally urged downwardly by spring 31. When the rod is elevated the pin 29 will be withdrawn from engagement with the cam 28 and the clutch collar urged by its spring 32 will move into clutching engagement with the gear 24. If the plunger

rod is held elevated the drive of shaft 25 will be continuous, but if it is released the pin 29 will engage the peripheral surface of the flange of the clutch cam until the latter 5 has rotated under it far enough to let it ride off and drop to its lowest position where it is engaged by the face of the cam. This occurs at the lowest portion 33 of the cam face. Continued rotation of the shaft for a 10 further quarter turn, with the pin now engaged by the cam face will result in the clutch collar being withdrawn from engagement with the gear 24 whereupon the shaft 25 will come to rest and remain stationary 15 until the rod 30 is again elevated when the shaft 25 will again be rotated one hundred and eighty degrees and so on. Thus a momentary lifting of the plunger rod 30 produces one half rotation of shaft 25. Referring to Fig. 2 it will be seen that the upper end of the rod 30 is connected to a crank arm 34 fixed to the trunnion 35 of the control board 6, so that to procure a half turn of the shaft 25, at any time, it is merely necessary to depress momentarily the board 6. The spring which elevates the plunger rod 31 serves to hold the control table in its normal horizontal position and maintains it in such position with sufficient rigidity to enable it to serve as a work-support on which the garment can be arranged for presentation to the roll, and the table is wide enough for this use.

These half turn movements of the shaft 35 25 are utilized to effect the movement of the shoe toward and from the roll and to this end, referring now to Figs. 4 and 5, an eccentric 36 is secured to the end of shaft 25 outside the transmission housing but within 40 a suitable protecting casing and an eccentric rod extends rearwardly from the eccentric strap into operative engagement with a crank arm 37 secured to the rock shaft 11 or formed as an extension of the arm 10. In 45 order that the shoe may act yieldingly on the roll, the connection between the eccentric rod and the crank arm includes a plunger member 38 which operates against a spring 39 within a guide sleeve 40, the latter being 50 rigidly connected to the arm 37. The end of the spring 39 bears against an adjustable screw stop as shown so that the ironing pressure may be varied to suit the conditions in hand. Furthermore, the eccentric rod is 55 articulated with a toggle joint 41 with its component links normally in their dead-center relation and beneath the joint is pivotally mounted a breaker member 42 operated by a push rod 43 slidably mounted on the 60 transmission housing and having a conveniently located knob 44 at its upper end. This push rod is preferably located adjacent the right hand end of the roll and somewhat above the feed table, and is normally urged 65 upwardly by a spring 45 which tends to hold

the breaker member away from the toggle, but should it be desirable at any time to effect the release of the shoe independently of its power drive, the operator is merely required to strike the knob which "breaks" the toggle and thereupon the shoe will fall well away from the roll. This arrangement is primarily designed to prevent the burning or scorching of the padding on the roll or of the article being ironed, should the current fail while the hot shoe is in pressing engagement with the roll. In addition, this opening of the shoe away from the roll facilitates cleaning and waxing of the shoe since when the toggle is broken, access may be readily had to every part of the ironing surface of the shoe. To return the parts to their normal positions the shoe may be manually restored to operative position by means of a knob handle 46 (Figs. 1, 4 or 6) which projects 85 from the left-hand end of the shoe.

Projecting from the rear of the transmission housing is a bracket 47 (Figs. 2 and 4) which provides a pivotal support for an upper table top 48, the latter being arranged to swing about the vertical post 49 and thus permit said table top to be utilized whether or not the machine is in operation. In Fig. 1 the machine is shown ready for use and the upper table top, supported by a collapsible leg 50, is conveniently located at the right hand of the machine for use in folding the articles to be ironed and, to hold the finished work, the drying rods 51 housed in holes in the end of the table top can be pulled out as shown when needed. When the ironing operation is completed the drying rods are pushed home, the leg 50 collapsed and the table top swung back over the machine to the position shown in dotted lines in Fig. 1 where it protects and conceals the ironing elements and where it may of course be used as an ordinary table.

As stated above the shoe is preferably heated electrically and as shown in Fig. 1, individual heating and motor switches are mounted on a switch plate 52 conveniently located on the front of the transmission housing where they are readily accessible to the operator.

In operating the machine flat work is arranged substantially evenly of the length of the roll and then, with the motor switch in the on position, the shoe previously heated and the roll drive clutch 20-19 engaged, the shoe is caused to move forward by depressing the control board as above explained, the work being smoothed and straightened with the hands as it is fed between the shoe and roll. To prevent injury to the operator, however, should the fingers come in contact with the hot shoe when the articles are being straightened or guided, the upper or leading edge of the shoe is provided throughout its length with a strip of heat insulating material 53

(Fig. 6), which may be of bakelite or other suitable material and is formed as a continuation of the general crescent shape of the shoe so that it may help to guide the work under the latter.

5 As regards articles requiring to be ironed on the bias, or, in general, pieces other than flat work, the ironing can be readily effected at the left-hand or open end of the roll (Figs. 1 and 6), the goose-neck support at that end readily permitting the work to be set as required on the end of the roll or if necessary slipped right over the roll 7 as in the case of skirts or the like.

10 15 Again, certain articles—pleated skirts for example—may require pressing in set forms or arrangements. Articles of this nature are arranged on the roll and then, with the roll drive clutch disengaged and consequently the roll stationary, the shoe is operated as before by a slight pressure on the control board. When the article is sufficiently pressed the shoe is released by another slight pressure on the control board, the roll manually rotated 20 to advance the unpressed portion of the garment and the shoe again operated.

Having now described my invention I claim:

1. In an ironing machine the combination 30 of a rotatable roll, a shoe movable toward and from the roll, an electric motor, connections between the motor and roll and the motor and shoe respectively for effecting the rotation of the roll and the movement of the shoe, a 35 work supporting feed table movable to control the connections between the motor and shoe and means independent of said feed table for controlling the drive connections between the motor and the roll.

40 45 50 55 2. An ironing machine comprising in combination a table-top base, a gear housing mounted on and above the base adjacent one end thereof, a rotatable roll having one end journalled in said housing, a shoe supported on the base for movement toward and from the roll, an electric motor on the base having a drive shaft extending into the housing, said shaft having operating connections respectively with said roll and shoe, a pair of clutch devices in said housing controlling respectively the motor-roll and motor-shoe connections, a movable work-supporting feed table mounted above the base adjacent the roll and arranged to control one of said clutches and means independent of said feed table for controlling the other of said clutches.

60 65 70 75 80 85 90 95 100 105 110 115 120 125 130 3. An ironing machine comprising a rotatable roll and a movable ironing shoe, a table top base beneath said roll and forming a clear space under it open front and rear, legs supporting said table and providing an unobstructed space between them adapted to accommodate a clothes basket, a motor, and a gearing assembly driven thereby on one end of the base including power means for driv-

ing the roll and advancing the shoe to the roll, a lever arm on the shoe connected with said gearing assembly above the base and at one end of said table and a depressible work table above said table top base having control connections to said gearing located wholly above the table top base and adapted to cause the shoe to advance to the roll.

4. In an ironing machine the combination of a rotatable roll, an ironing shoe and heating means therefor, means for effecting relative movement of the roll and shoe to move the same into and out of pressing engagement and a heat insulating member carried by the shoe to protect the operator from contact therewith and tapered to guide the work into the shoe.

5. In an ironing machine the combination of a rotatable roll, an ironing shoe and heating means therefor, roll driving means and a heat insulating member rigidly secured to and constituting the leading edge of the shoe to protect the operator in guiding the work to the shoe.

6. In an ironing machine the combination of a rotatable roll, an ironing shoe and heating means therefor, roll driving means and a heat insulating member mounted in advance of the shoe and shaped to form a continuous surface therewith.

In testimony whereof, I have signed this specification.

FREDERICK T. RUSSELL.
